UNITED STATES PATENT OFFICE.

HOWARD F. MARSTON, OF DAYTON, OHIO, ASSIGNOR TO MERCANTILE CORPORATION,
OF DAYTON, OHIO, A CORPORATION OF NEW YORK.

COMPOSITION CARRIER OR HOLDER.

1,187,640.

Specification of Letters Patent. Patented June 20, 1916.

Application filed September 10, 1915. Serial No. 49,882.

To all whom it may concern:

Be it known that I, HOWARD F. MARSTON, a citizen of the United States, residing at Dayton, in the county of Montgomery and 5 State of Ohio, have invented certain new and useful Improvements in Composition Carriers or Holders, of which the following is a full, clear, and exact description.

My invention relates to certain new and 10 useful improvements in holders or carriers for "composition." Composition may consist of regular type, linotype, stereotype, electro-type, monotype, plates or dies.

As an explanation of the objects of my invention, and to illustrate one use of my composition carrier or holder, I will refer to the manufacture of envelops. In the manufacture of envelops, it is customary to print corner cards or the sender's name and address on the corner of the envelops. The type for this printing may be set up on a linotype machine and then locked in a slug holder which securely holds the slugs while the printing operation is carried out. With 20 this sort of work, it is necessary to frequently change the type because small lots of envelops are printed for different persons and with corresponding different corner cards. In former machines, the type 25 have been locked in place by using a wrench, screw driver or other tool. This method is satisfactory on machines where the slug holder is easily accessible, but with certain types of machines, particularly those of the 30 continuous rotary type, the slug holder is necessarily located in an inaccessible part of the machine and the operation of changing composition becomes a difficult, dangerous and time consuming operation. The operator 35 must reach into the center or other inaccessible part of the machine through a closely arranged set of gears and rollers in order to reach the type. This, in addition, may be the cause of accidents if the machine accidentally starts, and nearly always 40 results in smearing the hands and clothing of the operator with grease and ink, which is also likely to come into contact with the product, thereby destroying it.

To the elimination of these defects and 45 for other ends I have devised my improved composition holder, which is adapted to be bodily withdrawn to the outside of the machine frame, where the composition is accessible and easily and safely replaced.

With such a construction the composition is always placed in a correct position in the holder and the cleaning of the holder and type or other composition is facilitated. In addition, the time of changing composition 60 is reduced and accidents to the operator are prevented.

My improved construction also eliminates the use of a wrench or other tool for changing composition, since the means for withdrawing the holder or carrier from the machine is also used for releasing the composition or type slugs.

It will be understood that my invention is not limited to envelop machinery, since 70 the improved holders are equally valuable in other printing machines.

In the drawings, Figure 1 shows a side view of the composition. The carrier is in the form of a mandrel and is shown removed from the printing machine and the driving shaft is shown broken off. Fig. 2 is a plan view of the mandrel. This view shows the frame of the printing machine, and the drive gear is also shown. The side 75 frames of the machine are shown closer together than the actual machine on account of lack of room. The mandrel in this view is shown withdrawn from the frame. Fig. 3 shows an end view of the mandrel and 80 the handle therefor. This view also shows in a diagrammatic manner some of the adjacent parts which surround the mandrel and necessitate the axial shifting of the mandrel in replacing the type. Fig. 4 shows 85 a side view of one of the linotype slugs. Fig. 5 shows an end view of the slug shown in Fig. 4.

In more detail, referring particularly to Fig. 3, 10 and 11 are the paper feeding rolls. 95 The paper advances along the dotted line and passes between the impression platen roll 13 and the mandrel shown by the dotted line 14. The type carried by this mandrel are inked by contact with ink roll 15, which 100 in turn is inked by doctor roll 16, which contacts with fountain roll 17 revolving in ink in the fountain 18. The mandrel impression roll and feeding rolls may be driven by suitable gearing not shown in this figure. 105 This figure illustrates the difficulty of replacing linotype slugs on the mandrel when it is remembered that the printing position is a considerable distance from the edges of rolls 10—11 and 21.

In Fig. 1, the mandrel is shown in a side view. It consists of the body portion 14 which has extending from each end the extensions 20 and 22 shown in dotted lines. Extension 22 and body portion 14 are connected by a taper 23. Over extension 22 is a sleeve 24, which sleeve is tapered at one end to correspond to taper 23. Sleeve 24 is pinned to extension 22 by pin 25. Extension 22 projects beyond sleeve 24 as shown at 26. It is this portion 26 which forms the journal for the mandrel when it is in "in" position. When in such position, 26 fits into bearing 27 of side frame 28 (shown in Fig. 2). A splined driving shaft 29 is rigidly connected with parts 22 and 26 and extends a considerable distance beyond 26. This splined shaft extends through the driving gear 30, which is slotted to receive the spline 20 and a collar 31 on the end of the shaft prevents the shaft from being entirely withdrawn from the gear. In this way the shaft and connecting mandrel are always kept in the same angular relation with the gear, regardless of whether the mandrel is withdrawn or in printing position in the side frames. It will be understood that the length of shaft 29 (shown broken off in Fig. 2) is dependent upon the distance that the mandrel is withdrawn from the machine and that when the mandrel is withdrawn that it is supported by the shaft 29 coöperating with gear 30, which is journaled upon frame 28 in any desirable manner.

Mandrel locking device.—Upon extension 20 is a bearing sleeve 21, which bearing sleeve is of such size that it will fit closely the bearing 32 in the left hand frame 28^a of the machine, when the mandrel is in "in" position. To facilitate the entry of sleeve 21 into bearing 32 when the mandrel is being returned to "in" position, the sleeve 21 is made slightly tapering, as shown at 33. The opposite end of bearing sleeve is enlarged to form a thrust shoulder 34. This portion of the sleeve also forms part of the clamping device as will hereafter be explained. Extension 20 of the body of the mandrel has secured to its end by a set screw a collar 35, which keeps bearing sleeve 21 from sliding axially on the said extension. Two posts 36 extend outwardly from part 34 of sleeve 21 and support a pin 37, which forms a pivotal support for a handle 38 which handle is spaced centrally between the posts by the bosses 39 (see Fig. 3). The posts 36 are both located below the center line of the mandrel for a purpose which will hereafter be explained.

The shoulder 34 of the sleeve is notched at 40 to allow the shoulder to pass a locking projection which consists of a screw 41 with a head 42 which extends outwardly from the frame 28^a (see Figs. 1 and 3). In moving the mandrel to "in" position, the handle

38 is turned until the notch 40 is in line with the head 42 of the screw 41. Then the mandrel is pushed in. To lock the mandrel in "in" position, the handle 38 is given a counterclockwise motion. This brings a cam edge 43 (shown in Figs. 2 and 3) into contact with the head 42 of screw 41 and securely holds the mandrel from outward movement.

Linotype slug holding mechanism.—As previously explained, this mandrel or slug carrier is adapted to carry a number of linotype slugs. These are of the shape shown in Figs. 4 and 5. They are tapered toward the base, as shown in Fig. 5, and at each end the corners are tapered at 45 and 46. The slug itself is indicated by the character 47. The base of the slug is indicated by character 48 and the ends by 49 and 50, respectively. To carry the slugs a slot is cut in the mandrel of a depth sufficient to bring the top of the type at the proper height for printing. The bottom of the slot in the mandrel 14 is shown by the dotted lines 48^a and 48^b in Fig. 1. It will be understood that the bottom of the slot is curved to correspond with the periphery of the mandrel to properly align the type slugs. The slugs 47 are placed in the slot completely filling the width of the slot as shown in Fig. 2. The tapered ends 46 of the slugs engage the tapered edge 23 of sleeve 24. This tapered edge forms a camming abutment and coöperates with other devices to secure the slugs in the slot. The end of the slot opposite tapered edge 23 is extended somewhat beyond the end of this type slug. This portion of the slot is also deepened somewhat, as shown at 51. Pivotaly mounted on the countersunk screw 52 and extending down into the portion 51 of the slot is a camming member 53. This camming member has a tapered nose 54, the taper corresponding to the taper 45 of the type slugs 47 and being adapted to engage over the tapered end of the slugs and hold them tightly against the cam abutment 23 at the opposite end of the slot. To hold the camming member 53 in engagement with the tapered ends 46 of slugs 47, I provide a plunger 55 which is pressed against the upper part of said camming member by means of a spring 56. Both spring 56 and plunger 55 are mounted in a cage 57 which is secured by a set screw in position in the mandrel.

Slug releasing mechanism.—In order to release the slugs 47, a plunger 58 is provided. This plunger 58 has free axial movement in a hole which is centrally located in the mandrel. One end of this plunger 58 contacts with the camming member 53 at a point below the pivotal support 52. It will be seen that by pressing inward on the plunger the camming member will be rocked in a counterclockwise direction,

thereby compressing spring 56 and moving the camming nose 54 to a position where it will be free from the type slugs. The slugs can then be lifted from the slot and new slugs inserted. To provide for easy access to the slugs when replacing them, the mandrel is notched at 59 on both sides of the slot.

For pressing the plunger 58 inward, I utilize the handle 38. When it is desired to release the type slugs, a latch 60 is first released from engagement with a hook 61 on the shoulder 34. This latch 60 is normally held in engagement with hook 61 by means of a spring, the latch being pivotally mounted at 62 on handle 38; a plunger 63 is longitudinally mounted in the handle 38. By pressing upward on the button on the end of plunger 63, the plunger will rock 20 latch 62 in a clockwise direction and release it from engagement with the hook 61. Thereafter the handle 38 can be rocked in a clockwise direction about its pivot 37. Pivot 37 being located in posts 36 below the center 25 line of the mandrel, a nose 64 projecting upwardly from handle 38 is adapted to force plunger 58 inwardly and release the slugs 47 in the manner previously explained.

It will be seen that my improved mandrel is particularly adapted to carry linotype slugs for contact with an impression platen and that the mandrel can be withdrawn from the frame of the machine when it is desired to replace, clean, or otherwise treat 35 the slugs or other composition. The improved mandrel also provides a simple means of locking and releasing the slugs.

For purposes of illustration, I have merely shown my composition carrier in connection 40 with linotype slugs, but it will be understood that other composition may be used as well. For example, if dies were used in place of the linotype slugs it would merely be necessary to provide the dies with 45 tapered corners like corners 45 and 46 of the linotype slugs.

It is to be understood that I do not limit myself to the precise embodiment shown and described. What I claim as my invention 50 is particularly pointed out in the appended claims.

I claim:

1. In a device of the class described, in combination, a rotatable linotype slug carrier, movable in the direction of its axis, means for clamping slugs to said carrier, means for clamping the carrier to prevent its movement in the direction of its axis, but permitting the rotation thereof, and 55 means for unclamping the slugs whereby they may be replaced.

2. In a device of the class described, in combination, a rotary linotype slug carrier movable into one position for printing and 60 to a second position for replacing the slugs,

means associated with said carrier for clamping the slugs thereto, means for clamping the slug carrier in operating position, said means being also adapted to unclamp the slugs when the slug carrier is shifted to 70 the replacing position.

3. In a device of the class described, in combination, a linotype slug carrier movable in the direction of its axis, means for securing slugs in position on said carrier, 75 a holding means for retaining said slug carrier in one axial position, and means for unclamping the secured slugs for replacing them.

4. In a device of the class described, in combination, a linotype slug carrier adapted to support a plurality of linotype slugs, said carrier being adapted to be clamped in one position during the printing operation, and manually operated means for unclamping 85 the said carrier and moving it to a more accessible position for changing type.

5. In a device of the class described, in combination, a mandrel, said mandrel having carrying means thereon for a plurality 90 of linotype slugs, journals for said mandrel located in the frames of a printing machine, clamping means for securing the said mandrel in place in said journals, and means for unclamping the said clamping means 95 and for withdrawing the mandrel from the frame for replacing the linotype slugs.

6. In a device of the class described, in combination, a mandrel forming a type carrier, resilient means for securing type to 100 said mandrel, means for clamping said mandrel in printing position, said mandrel, when unclamped, being adapted to be shifted to present the type in accessible position for replacement, and means associated with 105 the clamping means to coöperate with the resilient means and thereby release the type.

7. In a device of the class described, in combination, a mandrel, having a cam abutment, a spring pressed camming member 110 adapted to contact with type slugs and engage them against the aforesaid cam abutment, whereby the type slugs are secured to said mandrel, means for clamping the aforesaid mandrel against axial movement in the 115 frame of a printing machine, and means associated with the clamping means for moving the spring pressed camming member and releasing the type.

8. In a device of the class described, in combination, a type carrying mandrel adapted to be shifted laterally in the frame of a printing machine, a handle for shifting the aforesaid mandrel in and out, a clamping means operated by the handle, and a projection 125 on the frame of the machine for co-operating with the aforesaid clamping means and thereby securing the mandrel in position.

9. In a device of the class described, in 130

combination, a type carrying mandrel adapted to be shifted laterally in and out of the frame of a printing machine, a shaft extending from one end of the mandrel and adapted to drive the same, said shaft shifting with the mandrel and supporting one end thereof when the mandrel is withdrawn from the frame, a clamping device, and means associated with the mandrel and coöperating with the clamping device to prevent axial movement of the mandrel.

10. In a device of the class described, in combination, a type carrying mandrel, a sleeve revolvably mounted on said mandrel, a handle connected to said sleeve and adapted to rotate the same, means for clamping the sleeve to the frame by moving the aforesaid handle, a type clamping device on the mandrel, and means for unclamping the type by giving the aforesaid handle an additional movement.

11. In a device of the class described, in combination, a mandrel having a notch therein to receive linotype slugs, a pivoted locking device engaging one end of said slugs and thereby holding the same in the notch, a spring to press the said locking device toward the slugs, a handle to lock the mandrel in axial position, and means operated by the handle for moving the locking

device against the action of the spring and thereby release the linotype slugs.

12. In a device of the class described in combination, a composition carrier movable in the direction of the axis, means for securing composition to said carrier, means for retaining said carrier in one axial position and means for disengaging the composition securing means.

13. In a device of the class described in combination a composition carrier adapted to support composition in position for printing, said carrier being adapted to be clamped in one position during the printing operation and manually operated means for unclamping said carrier and moving it to a more accessible position for changing type.

14. In a device of the class described, in combination, a rotary composition carrier movable into one position for printing and to a second position for replacing the composition, means associated with the said carrier for securing the composition thereto, means for clamping the composition carrier in operating position, said means being adapted to release the composition when the carrier is shifted to the replacing position.

In testimony whereof I affix my signature.

HOWARD F. MARSTON.
